(57) **CLAIM**

The ornamental design for a tow hook, as shown and described.

DESCRIPTION

FIG. 1 is a front right quartering perspective view of the invention;

FIG. 2 is a left front quartering perspective view thereof;

FIG. 3 is a left side elevational view thereof;

FIG. 4 is a front elevational view of the invention;

FIG. 5 is a right side elevational view thereof;

FIG. 6 is a top plan view thereof;

FIG. 7 is a rear elevational view thereof; and,

FIG. 8 is a view of the underside of the invention.

Any broken lines are for illustrative purposes only and form no part of the claimed design.
